UNITED STATES PATENT OFFICE.

MERRITT M. TANNER, OF HAWKINSVILLE, NEW YORK.

DESIGN FOR A BOX.

SPECIFICATION forming part of Design No. 28,728, dated May 31, 1898.

Application filed April 2, 1898. Serial No. 676,250. Term of patent 14 years.

To all whom it may concern:

Be it known that I, MERRITT M. TANNER, residing at Hawkinsville, in the county of Oneida and State of New York, have invented 5 and produced a new and original Design for a Box, of which the following is a specification.

This invention is a new and useful design for a box which is particularly adapted for 10 smokers' use for containing a pipe, tobacco, and matches.

The leading feature of my design consists in the rectangular shape of the box, having 15 rounded corners, an angular partition extending longitudinally across the interior of the box and the transverse partition extending from the longitudinal partition to one side of the box.

The drawings hereto annexed fully illustrate my design, in which—

Figure 1 is a perspective view of a box constructed in accordance with said design. Fig. 2 is a top plan view.

Referring to the drawings, A represents

the box, essentially rectangular in shape and 25 having rounded corners B. The partition or wall C extends longitudinally across the interior of the box, said partition or wall having an angle D substantially at right angles and another angle E more acute than the 30 angle D.

F represents a partition extending from the partitional wall C to one side of the box.

G represents a rough surface upon the exterior of one end of the box.

A box constructed in accordance with the above design possesses both utility and novelty.

Having thus fully described my invention, what I claim as new, and desire to secure by 40 Letters Patent of the United States, is—

The design for a box, substantially as shown and described.

MERRITT M. TANNER.
